UNITED STATES PATENT OFFICE.

GEORGE P. ABORN, OF BOSTON, MASSACHUSETTS, ASSIGNOR TO THE BLAKE & KNOWLES STEAM PUMP WORKS, A CORPORATION OF NEW JERSEY.

AIR-PUMP.

No. 892,974.

Specification of Letters Patent.

Patented July 14, 1908.

Application filed September 14, 1907. Serial No. 392,829.

To all whom it may concern:

Be it known that I, GEORGE P. ABORN, a citizen of the United States, residing at Boston, county of Suffolk, and State of Massachusetts, have invented certain new and useful Improvements in Air-Pumps, fully described and represented in the following specification and the accompanying drawings, forming a part of the same.

10 This invention relates to an improved pump of that class used for pumping air or gases on the stroke in one direction, and liquid on the stroke in the opposite direction, the invention being especially designed for use in wet and dry vacuum pumps, although applicable for other purposes. In such wet and dry vacuum pumps, as used on condensers, connection is made with one part of the condenser for removing the air and uncondensed vapors, and with the bottom of the condenser for removing the discharge water, and these connections communicate with opposite sides of the pump plunger, if a single plunger be used, the air and uncondensed vapors thus being delivered from one side of the plunger, and the discharge water from the opposite side.

25 In a pump embodying the present invention, the air inlet is at the center of the cylinder by a central valveless suction passage, so that the air enters above the plunger when the latter is at the bottom of its stroke, and the water enters by a similar passage in the lower part of the cylinder when the plunger is raised, and flows from said passage into a smaller cylinder below the air cylinder from which the water is delivered on the down-stroke of the plunger, the large air plunger having a smaller extension or water plunger 40 by which the water is delivered. These pumps are preferably used in pairs with their plungers making alternate strokes, as by cranks set at 180° apart, by which a higher speed is possible and a greater efficiency secured, but the broader features of the invention may be embodied in a single pump, and may be used with driving mechanism of any type, as, for instance, in crank and fly wheel pumps, or direct acting steam driven pumps, 45 and either single, duplex or triplex.

50 The preferred embodiment of the invention in a two cylinder crank and fly wheel pump is illustrated in the accompanying drawings forming a part of this specification, and this construction will now be described

in detail and the features forming the invention then specifically pointed out in the claims.

In the drawings:—Figure 1 is an elevation of a twin or two cylinder pump embodying all the features of the invention; Fig. 2 is a vertical central section through one of the pumps.

Referring to the drawings, A, A are two pumps, shown as operated by the crank shaft B having cranks C set at 180° apart, so that the plungers are timed to move in opposite directions.

D is the main air inlet, and E the main water inlet, which are connected through pipes 10, 11 to the air and water inlets d, e of the respective pumps. The water delivery F at the bottom of each pump is shown as connected by pipe 12 to the air delivery G at the top of the pump, H being an open vapor pipe extending upward from the top of the pipe 12, the construction shown being adapted for a pump acting against a low head, as hereafter explained.

The air cylinder I, in which moves the large air plunger i, has below and continuous with it the smaller water cylinder K, in which moves the water plunger k forming an extension of the air plunger i, the two plungers being carried by the plunger rods 13 actuated from the motor and crank shaft. The air inlet d connects with the cylinder I centrally through the suction valveless passage 14 extending about the cylinder and open when the plunger i is in its lowest position, and the water inlet e connects with the space below the plunger i when the plunger is raised, through suction valveless passage 15 at the bottom of the cylinder. The water entering through suction valveless passage 15 flows downward into the water cylinder K, when the plungers i, k are raised, so that the lower end of the plunger k is raised above the top of the cylinder K, the plunger then being guided in the cylinder by the guide wings 1 on the bottom of the plunger. The air is delivered from cylinder I on the up-stroke through head delivery valves 2 to the air delivery G, and the water is delivered from water cylinder K and the chamber 16 below it on the down-stroke of the plunger, through delivery valves 3 to the water delivery F.

It will be seen that the invention provides a very small and compact construction, in

which the plunger which discharges the water may be proportioned for handling water only, thus assuring the filling of the water cylinder and securing a high efficiency, and 5 which provides for large valve area for discharging the water, so that the pump may run at a high speed. The pump is also well adapted for discharging against a considerable head, which is frequently necessary in 10 this class of pumps, the small water plunger being of great advantage in such cases by reducing the surface against which the head pressure is exerted.

If the pump is to deliver against any considerable head, it will be understood that the air delivery G will not be connected to the water delivery F, but that the air and water deliveries will be entirely separate. With 15 low heads, however, the connection of the two deliveries, as shown, is convenient.

With two pumps connected as shown, and with their plungers timed for simultaneous strokes in opposite directions, the down stroke of one plunger *i*, after the plunger *k* 25 has entered the small cylinder K, acts to push the water from below the plunger *i* to the other pump cylinder, and thus aids in filling the lower portion of the other cylinder. A higher rotative speed is thus possible, and a greater efficiency secured.

While the invention is intended especially for wet and dry vacuum pumps of that class in which air and water are taken from the condenser by separate connections, and the 35 invention is illustrated as thus applied, and certain specific features of the invention are limited to such a construction, a single valveless suction passage may be used through which both the air and water enter, the air 40 naturally rising and entering above the air plunger and the water below the air plunger. With separate air and water connections, also, the admission of water to the cylinder K may be controlled by suction valves of any 45 suitable form, within the invention, considered broadly.

Other modifications may be made within the invention defined by the claims.

What I claim is:—

50 1. A pump having a cylinder of two diameters, the upper larger portion forming an air cylinder and the lower smaller portion a water cylinder, upper and lower passages for admitting air and water to the air cylinder, a 55 plunger in the air cylinder acting to open the air passage on its down stroke and the water passage on its up stroke for the admission of air and water, and to deliver air on the up stroke, and a smaller plunger for delivering 60 water from the water cylinder on the down stroke.

2. A pump having a cylinder of two diameters, the upper larger portion forming an air cylinder and the lower smaller portion a water cylinder, connections for admitting air 65 and water to the air cylinder, a plunger in the air cylinder acting to admit air on its down stroke and water on its up stroke, and to deliver air on the up stroke, a smaller plunger for delivering water from the water 70 cylinder on the down stroke, and delivery valves and a delivery chamber surrounding the water cylinder.

3. The combination of two pumps, each pump having a cylinder of two diameters, 75 the upper larger portion forming an air cylinder and the lower smaller portion a water cylinder, connections for admitting air and water to the air cylinders and connecting the cylinders of the two pumps, plungers in the 80 air cylinders acting to admit air on their down stroke and water on their up stroke, and to deliver air on the up stroke, and smaller plungers for delivering water from the water cylinders on the down stroke, the plungers of 85 the two pumps being timed to move simultaneously in opposite directions.

4. A pump having a cylinder of two diameters, the upper larger portion forming an air cylinder, and the lower smaller portion a 90 water cylinder, suction connections including a valveless suction air passage for the air cylinder, a plunger in the air cylinder acting to admit air on its down stroke and deliver air on its up stroke, and a smaller plunger for delivering water from the water cylinder on its 95 down stroke.

5. A pump having a cylinder of two diameters, the upper larger portion forming an air cylinder and the lower smaller portion a 100 water cylinder, connections for admitting air and water to the air cylinder, a plunger in the air cylinder acting to admit air on its down stroke and water on its up stroke, and to deliver air on the up stroke, and a smaller 105 plunger for delivering water from the water cylinder on the down stroke.

6. The combination with the valveless suction, air cylinder I and water cylinder K, below the air cylinder, of plunger *i* for the air 110 cylinder, plunger *k* for the water cylinder on the bottom of plunger *i*, chamber 16 below the cylinder K, and delivery valves for the air and water cylinders.

In testimony whereof, I have hereunto set 115 my hand, in the presence of two subscribing witnesses.

GEORGE P. ABORN.
